UNITED STATES PATENT OFFICE.

FELIX O'DONNELL, OF PAWTUCKET, RHODE ISLAND, ASSIGNOR OF ONE-HALF TO SUSAN A. BROWN, OF PAWTUCKET, RHODE ISLAND.

WEFT-REPLENISHING MECHANISM FOR LOOMS.

SPECIFICATION forming part of Letters Patent No. 767,425, dated August 16, 1904.

Application filed February 3, 1903. Serial No. 141,781. (No model.)

To all whom it may concern:

Be it known that I, FELIX O'DONNELL, a resident of the city of Pawtucket, in the county of Providence and State of Rhode Island, have invented certain new and useful Improvements in Weft-Replenishing Mechanism for Looms; and I do hereby declare that the following is a full, clear, and exact description thereof, reference being had to the accompanying drawings, and to the letters of reference marked thereon, which form a part of this specification.

This invention relates to looms for weaving, more particularly to that class of looms which are provided with mechanism for automatically replenishing the shuttle with either cops or bobbins or for replacing or exchanging shuttles containing full cops for those containing empty ones.

The object of the invention is to increase the capacity of the loom by providing means whereby the shuttle will positively come to a full stop or rest in a certain position for a definite period, so as to make possible and practical the replenishing of the weft-thread in the shuttle when the loom is running at a high velocity. It is fully described in this specification and illustrated in the accompanying drawings.

Figure 1 is a side elevation of a loom with automatic replenishing mechanism on the right end and a shuttle-box separate from the lay and fixed to the loom-frame. Fig. 2 is an enlarged detail view of the fixed shuttle-box. Fig. 3 is a perspective view of the mechanism which operates the swell on the fixed shuttle-box and illustrates its connection with the swell-operating mechanism which moves with the reciprocating lay, a portion of said lay being dotted in position. Fig. 4 shows a plan view of the lay at its extreme backward position and in line with the fixed shuttle-box. Fig. 5 shows a plan view of the lay in its forward position, with the shuttle remaining at rest in the fixed box in position to receive a full cop.

In the construction, A A are the end frames of the loom, and C is the arch, on which may be supported a filling or replenishing mechan-

ism of any particular construction; but I prefer to show that described and illustrated in my patent of March 18, 1902, No. 695,696. On one end of the arch is rotatably mounted the cop-holding wheel D, on the periphery of which are a series of spring cop-holders. This wheel is actuated in the manner and by the mechanism more particularly described in my patent above referred to.

B is the lay, at one end of which is the fixed shuttle-box E, which box is separated from said lay and held in position on the loom-frame in a line with the lay when it is approximately at the end of its backward stroke. (See Fig. 4.) The other box, R, is attached to the other end of the lay B. The shuttle b is thrown back and forth across the loom in the usual way by action of the picker-sticks e and f through the rotating cam-shaft F and the cams d and d'. The picker-stick f oscillates with the lay B in the usual way, while the picker-stick e simply reciprocates in the fixed shuttle-box E.

e is the full cop, which is to be struck down into the shuttle by the automatic filling mechanisms above mentioned when it is time for replenishing said shuttle.

In the connection between the fixed and the moving shuttle-boxes is a finger G, fixed on a short shaft g. The upper end of said finger engages the swell E' on the stationary shuttle-box. On the inner end of this short shaft g, which is journaled in the frame, is fixed a lever H, the outer end of which is pressed upward by the action of the spiral spring h, coiled around the rod i and supported by the bracket I, through which rod i works. Resting on the inner end of this lever H is the lever J, which is fixed to the end of shaft j, which shaft is held in bearings on and moves with the lay. Shaft j is held in bearings on and extends along the back side of the lay B.

K is the ordinary dagger, mounted on shaft j and normally held down by the spring k in position to engage the frog l (which is connected in the usual way to the starting-lever and brake, not shown) when the latter moves forward, providing the shuttle is not in either of the boxes.

L is the ordinary swell-actuating finger, which in this case is mounted on and fixed to the end of shaft j and engages the swell of the shuttle-box that moves with the lay. 5 When the shuttle is in this box, the upper end of this finger L is pressed outward, raising the dagger K clear of frog l, which is the usual operation of this finger in the ordinary loom. When the shuttle is in this box on the lay, 10 the mechanism actuated by the swell is entirely separate and independent from the mechanism on the fixed shuttle-box; but when the shuttle is in the fixed box the mechanism connected to and operated by the swell E' is 15 thrown in a position to coöperate with that on the lay and raise the dagger, through the lever J and shaft j, so it will not engage the frog l as the lay again moves forward.

In my construction, where one box is stationary and one moves with the lay, I so construct my swell-actuating mechanism that the fingers L and G will act on their respective boxes separately and independently, except when the lay is in the position where the shuttle is thrown across, at which time both of said swell-fingers act in conjunction with each other, through the engagement of the lever J with the lever H, to control the action of the dagger K. The spring h keeps a constant 25 tension on the swell of the fixed shuttle-box, while the spring k acts on the moving box. When the shuttle enters the fixed box, the swell is opened and the dagger K is raised and held out of engagement with the frog l through the finger G, levers H and J, and shaft j, and when the shuttle is in the moving box the dagger K is raised and held up by the finger L, at which time there is no action of the mechanism on the fixed box. 30

40 In order to pass the shuttle successfully into and out of the fixed shuttle-box E, the lay B should be at its extreme backward stroke when the shuttle enters and leaves this box—that is, when the shuttle is to be thrown from the moving box R on the lay into the fixed box E the cam d' is set a trifle in advance of the stroke of the lay and throws the shuttle just before the crank has reached the top center, so that by the time the shuttle has 45 passed through the shed and is ready to enter the fixed box the lay is at its extreme backward stroke and in line with said box, which the shuttle enters squarely. Here the shuttle remains while the lay makes a forward stroke without it, and as the lay returns and the crank reaches the limit of its extreme backward stroke, or approximately so, the shuttle is thrown out of the fixed box onto the lay which is in line with it. By the time 55 the shuttle has traveled across into box R the lay has again started on its return stroke, which movement of course does not effect the entering of the shuttle into box R in the lay. This operation is repeated with each 60 pick of the loom, and by a proper and pre-

cise setting of the cams the shuttle is thrown into and out of the fixed box without difficulty.

In looms containing automatic weft-replenishing mechanism it has been found difficult to replace the cop or bobbin in the shuttle when the loom is running at a high speed on account of the extremely-limited time allowed for the replenishing mechanism to act. 70

To increase the time of the rest or dwell of the shuttle in which to replenish the weft-thread, I construct one shuttle-box, E, separate from the lay and place it on the same side of the loom with the replenishing mechanism and attach or fix said box to the loom-frame, 75 where it may receive the shuttle when the lay comes in line with it at the end of its inward stroke and hold said shuttle at rest in position to be operated on by the replenishing mechanism during the time the lay continues to make its whole stroke forward and back again in line with the box, at which time the shuttle is thrown out of the fixed box across the lay into the box on the other end of the lay by the action of the picker-stick e in the usual way. By this arrangement of the stationary shuttle-box I cause the shuttle to dwell for a substantial period many times that obtained by the old method where the shuttle travels with the lay and 80 its actual rest being only for the instant that the crank is passing the center. 90

This invention is extremely practical and simple in construction, and by its application the efficiency and capacity of the loom are 100 greatly increased.

Having thus described my invention, what I claim as new, and desire to secure by Letters Patent, is—

1. In a loom the combination of a stationary 105 shuttle-box independent of the lay and fixed to the loom, a shuttle-box on the opposite end of the reciprocating lay, a swell on each of said boxes, and means for operatively connecting the swell on the stationary box with that of the reciprocating box. 110

2. In a loom the combination of a stationary 115 shuttle-box independent of the lay and fixed to the loom, a shuttle-box on the opposite end of the reciprocating lay, a swell on each of said boxes, and means for operatively connecting the swell on the stationary box with that of the reciprocating box, said means coming into operative relation as the lay approaches the rear end of its stroke. 120

3. In a loom, the combination of a stationary 125 shuttle-box, a shuttle-box to move with the lay, a swell on each of said boxes, and mechanism for operating the swells of each box independent of each other, each independent mechanism to be brought into coöperative relation with each other at predetermined intervals.

4. In a loom the combination of a stationary 130 shuttle-box, independent of the moving lay,

and held in a fixed position on the loom, a shuttle-box on the opposite end of the reciprocating lay, and means for operatively connecting the swell on the stationary shuttle-box

5 with that of the reciprocating box, so that they may operate on each swell separately and independently except when the shuttle is thrown, at which time they work in conjunction with each other, substantially as de-
10 scribed.

5. In a loom the combination of a stationary shuttle-box independent of the moving lay and held in a fixed position on the loom, a shuttle-box on the opposite end of the recip-
15 roating lay, a swell on each of the shuttle-
boxes, and means located on the lay to move with it and operatively connected to the swell on its said shuttle-box, separate means lo-
20 cated on the stationary shuttle-box and oper-
atively connected with the swell in said box, and arranged to operate in conjunction with

said moving means to raise the dog and prevent the stopping of the lay when the shuttle has entered the said stationary box, sub-
stantially as described.

25

6. In a loom, in combination, a stationary shuttle-box, a shuttle-box to move with the lay, a swell on each of said boxes, a swell-oper-
ating finger and a dog operatively mounted to reciprocate on the lay, and a finger oper-
atively mounted to act on the stationary box,
each finger arranged to operate independent
of the other, except at the time the shuttle is
being thrown across the lay, at which time
each independent mechanism is in the proper
position to coöperate with the other.

In testimony whereof I have hereunto set
my hand this 26th day of January, A. D. 1903.

FELIX O'DONNELL.

In presence of—

HOWARD E. BARLOW,
CHAS. P. DAY.
